MECHANISM FOR CLAMPING MOBILE UNITS TO RAILS

Henry J. Perazzoli, Philadelphia, Pa.

Application March 21, 1936, Serial No. 70,017

8 Claims. (Cl. 51—178)

This invention relates to mechanism for clamping mobile units to the rails of a trackway. The invention is especially concerned with the provision of a novel clamping mechanism particularly adapted for application to a mobile unit carrying means for operating on a rail, such for example as a track grinder.

One of the primary objects of the invention is the provision of a simple, effective and readily actuated and released clamping mechanism for mobile units of the type above referred to.

Another object of the invention is involved in the provision of means whereby the clamping mechanism may readily be actuated to clamping position and, upon release of the operating member, will automatically become disengaged from the rail. This object and the object stated just above are both of importance in facilitating movement of the mobile unit from place to place along the rails, so that a minimum of time is lost during such movement. This, of course, is of especial importance where the traffic carried by the trackway is heavy, i. e., where trains or cars pass at frequent intervals. In such event, the machine for operating on the rails must, of course, be removed, and the quick action clamping mechanism of this invention is of importance in reducing the time necessary to unclamp, remove the machine and, after passage of a train, return the machine to the rail and re-clamp.

Still further the invention has in view arranging the several parts of the clamping mechanism in such manner that they may be raised substantially clear of the rail on which the mobile unit is adapted to ride, whereby the unit may be readily shifted or moved along the rails, over switches, etc.

Still other objects and advantages of the invention will be apparent from a consideration of the nature of the equipment with which the clamping mechanism is particularly adapted for use. In a rail grinding machine, for example of the caterpillar type having a series of bricks or equivalent abrasive means adapted to move on the surface of the rail longitudinally thereof, the grinding action exerts a very powerful driving force, tending to carry the machine along the rail or rails. With this in mind, the invention provides a clamp which, while having the desirable quick action, at the same time exerts a very substantial clamping force in order to resist the driving tendency of the grinding operation.

In addition to the above, in certain machines which are adapted to be positioned and operated more or less manually, for example by an operator

standing at an end of the machine, the invention further makes provision whereby the operator positioned as aforesaid may conveniently actuate the clamping mechanism. In other words, an operator positioned at an end of the machine in position to take care of other controls on the machine or to maintain the machine in an upright position may, with the improved clamping mechanism, actuate the clamp without leaving his post. To further facilitate complete control of the machine by such an operator, the invention provides an operating element for the clamp which is located for convenient actuation by the foot of the operator, thus leaving his hands free to manipulate other controls or aid in supporting the machine in its proper operative position.

How the foregoing objects and advantages are attained, together with others which will occur to those skilled in the art, will be more apparent from a consideration of the following description making reference to the accompanying drawing, in which—

Figure 1 is a side view of a portion of an end of a grinding machine adapted to ride on a rail, to which machine the clamping mechanism of this invention has been applied, various parts being shown in vertical section to illustrate the arrangement;

Figure 2 is an end elevational view on an enlarged scale of the machine taken from the right of Figure 1, this view also showing the clamping mechanism in elevation; and

Figure 3 is a vertical sectional view taken substantially as indicated by the section line 3—3 on Figure 1.

Various features of the grinding machine illustrated form no part of the present invention per se, these being described and claimed in my co-pending application Serial No. 46,992, filed October 28, 1935 now Patent No. 2,114,454, issued April 19, 1938. Some of the structure of a machine of this type is, however, illustrated in the drawing in order to bring out the cooperative relationship existing between those parts and the improved clamping mechanism.

The machine incorporates an endless series of bricks 4 of abrasive or like material, carried by a chain or the like 5 which is adapted to ride on sprockets or equivalent supports in an oval path, one run of which overlies the rail R in position to grind the surface thereof. This grinding portion of the machine proper is supported on framing 6 which is movable vertically with respect to an additional frame incorporating longitudinal

members 7 and uprights 8. Each upright carries a roller or wheel 9 adapted to ride on the rail, as clearly seen in Figures 1 and 3. The framing 6 incorporates slide or guide members 10 having guide flanges 11-11 adapted to embrace the upright 8 and thus provide for relative vertical sliding movement of the two frames.

Each upright 8 is further provided with a vertically elongated slot 12 through which an ear 13 projects, this ear being carried by member 10 (see Figure 1). Vertical adjustment of framing 6 and thus of the grinding unit itself may be effected by means of a shaft 14 threaded in a nut or collar 15 which is fixed as against rotation in the ear 13. Rotation of shaft 14 may be effected by a worm wheel 16 which in turn may conveniently be actuated by a worm (not shown) mounted on shaft 17, which latter is operated by hand wheel 18. It will be understood 20 that a mechanism similar to that just described is positioned toward each end of the machine so that the two ends of the framing 6 are carried up and down in unison in accordance with the adjustment of the hand wheel 18. A spring 19 reacting between the ear 13 and an abutment 20 serves to permit upward displacement of the framing 6 and the grinding unit, as when encountering an irregularity in the rail or the like.

While the clamping mechanism of the present invention may be applied to a wide variety of mobile units, it is peculiarly adapted to a unit in the general class described. In applying the clamping mechanism to this unit, I prefer to employ structure as follows.

35 A pair of arms 21 are pivotally mounted coaxially with the wheel 9 by means of the wheel shaft 22. These arms project away from the end of the machine and support a base plate 23 adapted to rest on the top surface of the rail and also a pair of flanges 24-24. The flanges in turn serve to support the clamping jaws 25-25 which are pivoted thereto by pins 26. The lower ends of the jaws preferably carry adjustable pointed bolts 27 which, upon movement of the lower ends of the jaws toward each other, engage the side faces of the rail to effect the clamping. The upper ends of the jaws 25 are curved inwardly and provided with angled end surfaces 28 which, in release position (see Figure 50 3) abut against each other at one corner to limit the movement in the releasing direction and which further cooperate with a wedge part 29 formed on the operating lever 30.

The operating lever is preferably carried more 55 or less directly from the upright 8 as by a bracket 31 having a pair of apertured ears 32 to which the lever is pivoted by a pin 33. Upon depression of the foot pedal 34 carried by the outer end of the operating lever, the wedge part 29 is driven 60 down in between the angled surfaces 28-28 and in consequence the upper ends of the jaws are spread and the lower ends thereof brought together to clamp the rail. A guide device 35 projects upwardly from the base and is provided 65 with a slot through which the operating lever passes, this guide device serving to limit movement of the operating lever in addition to its guiding function.

As best seen in Figure 3, a spring 36 is provided 70 for drawing the upper ends of the jaws 25 toward each other and thus releasing the clamp. An additional spring 37 serves to raise the operating lever 34 and also to pivot the entire 75 clamping mechanism about the wheel axis 22

and thus raise the clamping mechanism clear of the rails (see Figure 3).

In considering the operation of the mechanism it is first pointed out that in Figures 1 and 2 the structure is shown in clamping position, 5 i. e., in engagement with the rail, while in Figure 3 the mechanism is shown in released position and also raised about the pivot 22 away from the rail.

When the machine is brought to a point of use 10 and positioned on the rail, the operator standing at the right in Figure 1 may conveniently effect clamping by depressing the foot pedal 34. This action, as above stated, spreads the upper ends of the jaws and forces the bolts 27 (see Figure 2) against the side faces of the rail. The grinding may now take place and the machine will be rigidly maintained in the desired location along the rail. While maintaining the clamp in its clamping position as just described, the 20 operator may conveniently employ his hands to keep the machine in its proper operative position, as by grasping the handle H or, if desired, he may manipulate the wheel 18 for the purpose of adjusting the height of the grinding unit proper. When it is desired to move the machine to a new spot along the rail, the operator merely releases the foot pedal enough to disengage the clamping bolts 27. The machine may then be 25 rolled on its rollers 9 to the new location and the foot pedal again actuated to effect clamping to the rail. When it is desired to move the machine from place to place by travel along the rail, the operator's foot may be completely removed from the pedal 34 and in this event 30 the spring 37 serves to raise the lever 30 until this lever abuts the upper part of the guide 35. This in turn causes the entire clamping mechanism to pivot upwardly about the pivot 22 (the axle for the wheel or roller). As seen in Figure 40 3, this upward movement is sufficient to bring the lower ends of the jaws 27 entirely clear of the upper side of the rail R. By virtue of this upward displacement the machine may now be 45 transported from place to place along the rail without danger of fouling of any part of the clamping mechanism on switch parts, crossings, or the like.

From the foregoing it will be seen that the invention provides not only an effective and powerful wedging or clamping action, but further incorporates these desirable features in a device which at the same time has quick action, so that minimum time loss is necessary in moving the equipment from place to place or in removing the equipment entirely from the rail so 55 as to permit the passage of a train or any other railway vehicle.

I claim:

1. In a machine for operating on a rail of a 60 trackway, a supporting wheel mounted on the machine and adapted to ride on the rail, a mechanism for clamping the machine to the rail including a frame pivotally mounted coaxially with said wheel for movement upwardly and downwardly with respect to the rail, a pair of clamping jaws carried by the frame at least one of which is movable toward and away from the rail with the frame in a lower pivotal position of the frame, and means for effecting relative movement of the jaws to provide for clamping and release of the rail. 65

2. In a machine for operating on a rail of a trackway, a supporting wheel mounted on the machine and adapted to ride on the rail, a mech- 75

anism for clamping the machine to the rail including a pivotally mounted frame, a pair of clamping jaws carried by the frame at least one of which is movable toward and away from the rail with the frame in a lower pivotal position, means for effecting relative movement of the jaws to provide for clamping and release of the rail, and means urging said frame and the jaws carried thereby to an upper pivotal position upon release of the operating means for the jaws.

3. In a machine for operating on a rail of a trackway, a supporting wheel mounted on the machine and adapted to ride on the rail, a mechanism for clamping the machine to the rail including a frame pivotally mounted for movement upwardly and downwardly with respect to the rail, a pair of clamping jaws carried by the frame at least one of which is movable toward and away from the rail with the frame in a lower pivotal position, and a base plate adapted to engage the rail in a lower pivotal position of the frame to support the clamping mechanism on the rail during actuation of the jaws.

4. In a machine for operating on a rail of a trackway, a supporting wheel mounted on the machine and adapted to ride on the rail, a mechanism for clamping the machine to the rail including a frame pivotally mounted for movement toward and away from the rail, said frame having a part adapted to rest on a rail in a lower pivotal position and being adapted to be raised to an upper pivotal position away from the rail, a pair of clamping jaws carried by the frame, means for effecting relative movement of the clamping jaws toward and away from the rail including an operating element adapted to effect clamping of the rail upon downward movement thereof and to release the jaws upon upward movement thereof, a spring reacting between a part of the machine and said operating element for raising the element to release the jaws, and interengaging means on the frame and said element for raising the former when the latter is raised by said spring.

5. In a machine for operating on a rail of a trackway, means for supporting the machine on the rail, mechanism for clamping the rail to secure the machine thereto, said mechanism being mounted for downward and upward pivotal movement, means for operating the clamping mechanism including an operating element positioned relatively low for foot actuation by an operator, and means normally moving the entire clamping mechanism including the operating element to a position above the rail when the operating element is released.

6. In a machine for operating on a rail of a trackway, a supporting wheel mounted on the machine and adapted to ride on the rail, a mechanism for clamping the machine to the rail including a frame mounted for downward and upward pivotal movement into and out of operative position with respect to the rail in which latter position the clamping mechanism is clear of the top of the rail, said frame having a part adapted to rest on the rail in the lower or operative pivotal position, a pair of clamping jaws carried by the frame, and means for effecting relative movement of the clamping jaws toward and away from the rail including an operating element adapted to effect clamping of the rail upon downward movement thereof and to release the jaws upon upward movement thereof.

7. In a machine for operating on a rail of a trackway, a supporting wheel mounted on the machine and adapted to ride on the rail, a mechanism for clamping the machine to the rail including a frame mounted for downward and upward pivotal movement into and out of operative position with respect to the rail in which latter position the clamping mechanism is clear of the top of the rail, said frame having a part adapted to rest on the rail in the lower or operative pivotal position, a pair of clamping jaws carried by the frame, means for effecting relative movement of the clamping jaws toward and away from the rail including an operating element adapted to effect clamping of the rail upon downward movement thereof and to release the jaws upon upward movement thereof, and means normally urging the operating element to an upper position.

8. In a machine for operating on a rail of a trackway, means for supporting and positioning the machine on the rail, a rail working tool carried by the machine, a mechanism for clamping the machine to a rail of the trackway, said mechanism including clamping jaws relatively movable to clamp the rail, the mechanism being movable generally upwardly and downwardly between a lower operative position in which the clamping jaws may engage the rail and an upper inoperative position in which the clamping jaws are clear of the top of the rail, and an actuating device for said mechanism including a single operating element providing upon actuation thereof for sequential movement of the clamping mechanism into operative position and then clamping of the rail by the jaws.
